SOCK OR SIMILAR ARTICLE OF KNITTED WEARING APPAREL

Frank Sydnor, Mount Airy, N.C., assignor to Renfro
Hosiery Mills Company, Mount Airy, N.C., a corporation of North Carolina

Application September 3, 1958, Serial No. 52,488

Term of patent 14 years

(Cl. D47—7)

The dominant feature of the design resides in the cuff portion shown in full lines in the drawings, said cuff portion is permanently distorted as shown.

I claim:

The ornamental design for a sock or similar article of knitted wearing apparel, substantially as shown and described.
